KNIFE SHARPENER

Emerson E. Case, Perry, N. Y., assignor to Robeson Cutlery Company, Inc., Perry, N. Y., a corporation of New York

Application July 23, 1952, Serial No. 20,735

Term of patent 14 years

(Cl. D37—1)

To all whom it may concern:

Be it known that I, Emerson E. Case, a citizen of the United States of America and resident of Perry, in the county of Wyoming and State of New York, have invented a new, original, and ornamental Design for a Knife Sharpener, of which the following is a specification, reference being had to the accompanying drawing, forming part hereof.

Fig. 1 is a top plan view of a knife sharpener, showing the new design;

Fig. 2 is a side elevational view thereof, viewed from one side; and

Fig. 3 is a side elevational view thereof, viewed from the opposite side, with a portion of the handle broken away for convenience of illustration.

I claim:

The ornamental design for a knife sharpener, substantially as shown.

EMERSON E. CASE.
